(57) **CLAIM**

The ornamental design for a tempering bin with lid as shown and described.

DESCRIPTION

FIG. 1 is a top view of the tempering bin with lid in accordance with the new design;

FIG. 2 is a top perspective view thereof;

FIG. 3 is a bottom view thereof;

FIG. 4 is a bottom perspective view thereof;

FIG. 5 is a side view thereof;

FIG. 6 is a front view thereof;

FIG. 7 is a back view thereof;

FIG. 8 is a top view of the tempering bin showing the lid removed;

FIG. 9 is a top perspective view thereof;

FIG. 10 is a bottom view thereof;

FIG. 11 is a bottom perspective view thereof;

FIG. 12 is a front view thereof;

FIG. 13 is a side view thereof;

FIG. 14 is a back view thereof;

FIG. 15 is a top view of the lid showing the tempering bin removed;

FIG. 16 is a top perspective view thereof;

FIG. 17 is a bottom view thereof;

FIG. 18 is a bottom perspective view thereof;

FIG. 19 is a front view thereof;

FIG. 20 is a side view thereof; and,

FIG. 21 is a back view thereof.
